UNITED STATES PATENT OFFICE

CHARLES F. LE FEVER, OF PLYMOUTH, MICHIGAN, ASSIGNOR TO DAISY MANUFACTURING COMPANY, OF PLYMOUTH, MICHIGAN, A CORPORATION OF MICHIGAN

GUN

Application filed October 14, 1929. Serial No. 399,635.

The invention relates to spring air guns of that type known as pump guns in which the compression of the spring is effected by the movement of a handle parallel to the barrel of the gun. The invention consists in various novel features of construction as hereinafter set forth.

In the drawings:

Figure 1 is a side elevation of the gun;
19 Figure 2 is a vertical longitudinal section through the frame and a portion of the barrel of the gun;

Figures 3 and 4 are similar views showing the parts in different positions of adjustment;
15 Figure 5 is a cross section on line 5—5 of Figure 2;

Figures 6, 7 and 8 are cross sections respectively on lines 6—6, 7—7 and 8—8 of Figure 4;

20 Figure 9 is an elevation showing the barrel and the handle guide bar detached;

Figure 10 is a perspective view of the air compression cylinder and spring;

Figure 11 is a perspective view of the 25 plunger and shank;

Figure 12 is a perspective view of a portion of the trigger locking mechanism, and

Figure 13 is a perspective view of a portion of the handle guide bar and sear support.

30 Figure 14 is a side elevation showing the stock and barrel of the gun detached and in knock-down position.

As shown, A is the false barrel preferably formed from a sheet metal blank and of substantially cylindrical form from end to end. B is a cylindrical guide for the pump handle which also is preferably formed from a sheet metal blank of cylindrical form from end to end arranged beneath the false barrel parallel

40 thereto. Secured within the rear portion of the member B is a member C formed up from a sheet metal blank being provided with a portion C' which fits within the member B and is spot welded or otherwise secured thereto and upwardly extending spaced flange portions C². At their forward ends these flanges are fashioned to telescopically engage the barrel A and to form a spring abutment. The member A is also provided with

45 a loop or bearing A⁴ which is telescopically

engaged by the forward end portion of the member B, thereby connecting the members A and B and holding the same in parallelism.

The member A on its lower side is slotted to receive the flanges C² and is further provided with depending flanges A' on opposite sides of the slot and having the notch A² therein. Within the barrel A there is secured

55 an abutment A³ which forms a bearing for the air compression cylinder D. This cylinder is telescopically engaged with the barrel A and is slidable therein. It is further provided with a depending flange D' preferably attached to a collar surrounding the cylinder and soldered or otherwise secured thereto.

60 The flange D' projects downward through the slot in the upper side of the member B. Within the barrel D is a piston or plunger E provided with the usual forwardly extending air tube E' which passes

65 through a central aperture in the abutment A³ and the rearwardly extending shank E² having a groove E³ near its rear end and the tapering head E⁴. The spring F is sleeved about the shank E² within the cylinder D

70 and at its rear end engages an abutment collar F' which bears against the member C. G is a tubular handle sleeved upon the member B and having a rearwardly extending apertured flange G' for engaging a tongue D² on the flange D'.

75 Thus to assemble the parts as thus far described the plunger E is placed within the cylinder D, the spring F is sleeved upon the plunger shank E² and the abutment collar F' is engaged with the rear end of the

80 spring. These parts are then telescopically engaged with the barrel A after which the member B is assembled by telescopically engaging the member C with the barrel and engaging the forward end of the member B

85 with the loop or bearing A⁴. At the same time the tongue D² is engaged with the slotted flange G' of the handle G so that when

90 said handle is slid rearward upon the member B it will carry with it the cylinder D and plunger E compressing the spring F against the collar F' and abutment C³.

95 The gun is provided with a stock member H and a frame member I, the latter being formed of sheet metal which in cross section

is an elongated loop adapted to receive the members A and B. The sear J is mounted between the flanges C² and is secured to a pivot J' passing through said flanges. The trigger K is mounted upon a pivot K' within the frame I and is so positioned that when the parts are assembled it will be in operative relation to the sear. The members are then held in this position by a pin or bolt L which passes through the frame through the notches A² in the flanges A' and a registering aperture in the flanges C².

With the construction as thus far described it will be understood that by drawing rearwardly on the handle G it will through the engagement of the tongue D² with the flange G' move the cylinder D rearward compressing the spring F against the collar F'. This movement also carries with it the plunger and its shank E². This will cause the sear J to engage with the notch E³ in the plunger shank to hold the plunger from return movement when the handle G is again moved forward. It is, however, desirable to lock the trigger during this operation as otherwise the sear might be disengaged accidentally and the spring released before the completion of the forward movement of the handle. Such a locking mechanism is formed by a member M which is arranged within the hollow member B and is slideable longitudinally thereof. The member M is preferably formed of a metal bar having down-turned flanges M' at its opposite ends and a slot M² in its forward portion which is engaged by the tongue D². Beneath the bar M is a spring latch bar N attached thereto and having at its forward end a portion N' for engaging the tongue D². The arrangement is such that when the handle G is drawn rearward upon the member B the tongue D² engaging a portion N' of the latch bar N will move the bar M rearwardly until it extends beneath a finger K² on the trigger K and further rearward movement will arrest it. The handle G is permitted to continue its rearward movement by disengaging the tongue D² from the spring latch bar N thereby permitting the carrying back of the cylinder and plunger to engage the plunger shank with the sear. During the forward movement of the handle G the bar M remains in position to lock the trigger until at the completion of this movement the tongue D² reaching the end of the slot M² will force the bar M forward withdrawing it from engagement with the finger K².

The gun as above described is one which simulates the appearance of a powder pump gun and is also a construction which is simple to manufacture and is easily operated. The fact that the handle G directly engages the tongue D² on the cylinder dispenses with the necessity for any complex intervening lever mechanism. On the other hand, as the direction of movement of the handle is parallel

with the axis of the barrel the cylinder may be moved backward and the spring compressed without too great labor on the part of the operator.

Another important feature of my construction is that the stock and barrel of the gun can be readily detached for convenience in assembly and in shipment. It will be noted that the members A and B are held in assembled relation to each other and to the frame of the gun by the shank bolt or pin L. Therefore by removing this bolt the barrel may be withdrawn from the frame and arranged in the position shown in Figure 14 which is convenient for packing and shipment.

What I claim as my invention is:

1. In a gun, the combination with a barrel, of a spring actuated plunger within said barrel, a tubular guide arranged beneath and parallel to said barrel, a handle sleeved upon said guide and adapted to compress said spring during its rearward movement, a hollow frame for receiving the rear end portion of said barrel and guide, a sear and trigger mounted in said frame in cooperative relation to said plunger and means for securing said barrel and guide in said frame permitting attachment and detachment thereof without disturbance of said sear and trigger.

2. In a gun, the combination with a barrel and a spring actuated plunger therein, of a tubular guide arranged beneath and parallel to said barrel, a handle sleeved upon said guide and adapted to compress said spring during its rearward movement, a member secured to said guide telescopically engaging the rear end of said barrel and forming a spring abutment, a sear mounted in said member, a hollow frame for receiving the rear end portions of said barrel and guide and secured thereto and a trigger within said frame for releasing said sear.

3. In a gun, the combination with a barrel, of a spring actuated plunger therein, a tubular guide arranged beneath and parallel to said barrel, a handle sleeved upon said guide and adapted during its rearward movement thereon to compress said spring, a member on said guide telescopically engaging the rear end of said barrel and forming a spring abutment, a bearing on said barrel for telescopically receiving the forward end of said guide, a hollow frame for receiving said barrel and guide and means for coupling the same together.

4. In a gun, the combination with a barrel slotted on its under side, of an air compression cylinder slideable within said barrel and having a flange or tongue projecting downward through said slot, a plunger within said cylinder and having a rearwardly extending shank, a spring sleeved upon said plunger shank, a tubular guide arranged beneath and parallel to said barrel, a handle sleeved upon said guide and engaged with said down-

- wardly projecting tongue to move said cylinder rearward and to compress the spring, a member on said guide telescopically engaging the rear end of said barrel and forming an abutment for said spring, a sear mounted in said member and engageable with the plunger shank when the spring is compressed, and a frame for receiving and securing to the rear end portions of said barrel and guide.
- 5 5. In a gun, the combination with a barrel slotted on its under side, of a cylinder in said barrel provided with a depending flange or tongue extending through said slot, a plunger within said cylinder, a spring for
- 10 said plunger, a tubular guide arranged beneath and parallel to said barrel and slotted on its upper side to receive said depending flange or tongue, a handle sleeved upon said guide and engaging said tongue to move said
- 15 cylinder rearward to compress the spring, a sear for engaging the plunger in the compressed position of the spring, a trigger for releasing said sear and a member slidale within said hollow guide and actuated by
- 20 said handle and tongue adapted to lock said trigger during the rearward and forward movements of said handle and to release the lock at the completion of the forward movement thereof.
- 25 6. In a gun, the combination with a barrel, a spring actuated plunger within said barrel, a guide arranged beneath and parallel to said barrel, a handle sleeved upon said guide and adapted to compress said spring during its
- 30 rearward movement, a stock, a hollow frame on said stock adapted to receive the rear portion of said barrel and guide, a sear and trigger mounted in said frame in cooperative relation to said plunger, and a cross pin ex-
- 35 tending through said frame and engaging said barrel to lock the parts in assembled position permitting attachment and detachment thereof without disturbance of said sear and trigger.
- 40 45 In testimony whereof I affix my signature.
CHARLES F. LE FEVER.
